TEAT CUP INFLATION PUNCH AND AIR VENT CLEANER

Daniel O. Norlander, 5707 N. Bond St.,
Fresno, Calif. 93726

Filed June 26, 1970, Ser. No. 23,694

Term of patent 14 years

Int. Cl. D8—99; D30—99

U.S. Cl. D49—22

FIG. 1

FIG. 2

FIG. 1 is a front plan view of a teat cup inflation punch and air vent cleaner in accordance with the invention; and FIG. 2 is a side plan view of the teat cup inflation punch and air vent cleaner shown in FIG. 1.

I claim:

The ornamental design for a teat cup inflation punch and air vent cleaner, as shown.
